DESIGN FOR A HANDBAG

William Tashman, Chicago, Ill.

Application December 21, 1942, Serial No. 109,095

Term of patent 3½ years

To all whom it may concern:

Be it known that I, William Tashman, a citizen of the United States, residing in Chicago, in the county of Cook and State of Illinois, have invented a new, original, and ornamental Design for a Handbag, of which the following is a specification, reference being had to the accompanying drawing, forming part thereof.

Fig. 1 is a front elevational view of the handbag showing my new design, in closed position.

Fig. 2 is a perspective view thereof in open position, showing the internal wall for the retention of the flap closure member, and

Fig. 3 is a rear elevational view thereof with the flap closure member extended.

I claim:

The ornamental design for a handbag, substantially as shown.

WILLIAM TASHMAN
